COMPUTING MACHINE

Robert H. Strother, Montclair, N. J., assignor to
 Remington Typewriter Company, Ilion, N. Y., a
 corporation of New York

Application July 28, 1927, Serial No. 209,008

25 Claims. (Cl. 235—59)

My invention relates to computing machines and it has for its principal object to provide improved clearance proof mechanism for such machines. To the above and other ends my invention consists in certain features of construction and combinations and arrangements of parts all of which will be fully set forth herein and particularly pointed out in the claims.

My invention is here shown applied to a Remington combined typewriting and computing machine of the sort described in the patent to Wahl No. 1,270,471 dated June 25, 1918, and which machine has for a number of years been marketed extensively. Except as hereinafter described, the machine is or may be constructed substantially as shown in the Wahl patent but the invention may also be embodied in machines that differ considerably from that patent.

In the present instance clearance proof mechanism, not shown in the Wahl patent, is applied to the cross totalizer, which in the Remington machine is a jumping totalizer. This totalizer or register as it has been manufactured for some time contains a feeler device including a finger projecting upward therefrom, which finger occupies a rear position when the totalizer is clear and a forward position when the totalizer is not clear. I provide means whereby on the jump-back of the cross totalizer this finger controls two different signals. If before writing and computing the last number the totalizer had not been clear but the writing of said last number cleared the totalizer and therefore caused the said finger to be moved to rear position, then on the jump-back of the totalizer the machine will automatically be caused to print a star. Nothing further will happen in the clear signal mechanism until at some reciprocation of the cross truck a number is registered in the cross totalizer. The registration of this number will cause said finger to move to its not clear position and on the following jump-back of the cross truck the finger will operate mechanism which will cause a square to be automatically printed after the number. The clearance proof mechanism will remain inactive even though several numbers may be added into the cross totalizer, and until at some operation of the machine said cross totalizer is cleared. On the succeeding jump-back of the cross truck the star will be automatically printed immediately following the number that cleared the totalizer. In short, a star is automatically printed after every total 55 the writing of which clears the totalizer, and a

square after the first number to be registered after a clearance of the totalizer.

The printing of the clear signals is preferably done by power which may be applied in any suitable way. In the present instance, the power is derived from a continuously rotating drum.

In the accompanying drawings,

Fig. 1 is a front elevation containing a more or less conventionalized showing of a portion of the Remington typewriting and computing machine but with some parts in section, some broken away, and many parts omitted.

Fig. 2 is a similar view from the right-hand side of the machine.

Fig. 3 is a perspective view showing parts of the clearance proof mechanism on a larger scale.

The Remington machine, as manufactured at present, comprises a #12 Remington typewriter having a base 5, corner posts 6, top plate 7, and a platen 8 mounted on a carriage 10 which runs on stationary rails 11. The printing keys 12 are on key levers 13, Fig. 1, and are connected with bell cranks 14 which operate type bars 15. The two end type bars 16 and 17, shown in Fig. 2, are not connected with key levers but are operated automatically to print the clearance signals as will hereinafter be described.

The main frame of the computing mechanism comprises a casting 18, secured to the top plate 1, this casting being shown in section in Fig. 2 a fragment of its right-hand end being shown in Figs. 1 and 3. The main truck 20 is mounted and guided in the usual manner, being connected with the carriage 10 by means of arms 19. This truck supports any suitable number of vertical totalizers, four being shown in the present instance and marked 21, 22, 23 and 24. These totalizers travel over the main master wheel 25. The cross truck 26 is here conventionally shown in the form described in the patent to Hart No. 1,464,095 dated August 7, 1923, and having rollers or wheels 27 running on stationary rails 28. This truck carries the usual cross footing totalizer or register 30 in its travel over the cross master wheel 31. The cross truck is adapted to be picked up and dropped by the usual pick-up beam 32 which is picked up by each of the vertical totalizers and which has a pin 33 running in a guide slot 34 in a stationary piece 35, all as usual in this machine.

The slot 34 has the usual off-set which disengages the hook or pick-up beam from the vertical totalizer allowing the cross truck to be jumped back by the usual spring (not shown). The vertical totalizer in any desired column may have the usual subtraction cam 36 which acts on a follower 37

roller 37 to set the cross master wheel 31 for subtraction. The cross truck 26 has the usual bar 38 projecting rightward therefrom and acting to arrest the cross truck when it jumps back. 5 This bar is adjustable by means of a screw 39 and holes in the bar as is usual in this machine where it is customary to regulate the extent of the jump-back by shortening this bar for wide totalizers and lengthening it for narrow ones.

10 The cross totalizer 30 has in it clearance testing or detecting mechanism which with an exception that will be pointed out is constructed substantially like that shown in the patent to Poole No. 1,483,679 dated February 12, 1924. 15 Each dial 30 has one tooth of its pinion 41 made shorter than the rest, and these pinions are engaged by a comb 42 pivoted at 43 and articulated at 44 with an arm 45 pivoted at 46 and having an upstanding finger 47 projecting out through a 20 slot in the casing. A spring 48 presses the comb 42 against the pinions, and when all of said pinions stand at zero, so that each one has its short tooth in register with the comb, the parts will stand as shown in Fig. 2 with the finger 47 in its 25 rear position; but if any one or more of the wheels is at some other position than zero then such wheel or wheels will have a long tooth presented to the comb and will force said comb rearward which will rock the finger 47 forward from the 30 position shown in Fig. 2.

My improvements consist chiefly in the mechanism controlled by the finger 47. This finger during the reciprocations of the cross truck 26 has two paths of travel, a rear path when the 35 cross register 30 is clear and a front path when said register is not clear. I provide signal mechanism including two contact parts, one in the rear path adapted to be displaced by said finger on the first jump-back of the cross truck when 40 the register is cleared and the other in the front path adapted to be displaced by said finger on that jump-back which follows the registration of the first number in the totalizer; and when one of said contact parts is displaced from its path, 45 it replaces the other contact part in the other path. The result is that said signal mechanism is operated once only following each change in the state of the totalizer or register with respect to clear and not clear. This contact mechanism 50 can be made in several different ways, and it can control signals of several different sorts. The drawings show one form of contact mechanism and one sort of signal controlled by it, but the invention is not limited to that particular form 55 of mechanism or sort of signal.

The extreme right-hand end of the casting 18 has a regular frame plate 50 secure thereto by two screws 51. These two screws are utilized to secure to the casting a special sheet metal frame plate 60 or bracket 52, the main body of which lies behind and parallel with the casting bar 18 but whose right-hand end is bent forward and perforated for the purpose of being fastened by these screws. The left-hand end of the plate 52 may 65 be bent forward also as shown at 53 to contact with the rear face of the casting 18 to steady the piece 52.

In the space between the casting 18 and the plate 52 there are mounted on said plate three 70 bell cranks having upstanding arms 54, 55 and 56, all connected by a link 57 pivoted to each of said arms at 58. Each of these bell cranks consists of a piece of sheet metal so bent as to be pivoted at two points spaced apart on a fixed 75 pivot pin 60. A sleeve or washer 59 fastened by

a set screw on each pivot pin 60, prevents end-wise movement of the bell cranks. The right-hand bell crank has besides its upstanding arm 54 a horizontal arm 61 extending leftward from the pivot 60 and having its lower edge formed into a cam 62. The second bell crank has besides its upstanding arm 55 a horizontal arm 63 extending rightward from its pivot 60 and having its lower edge shaped into a cam 64. The cam 62 is in such position as to be engaged by the upper end 10 of the finger 47 when the latter is in its rearward or clear position and it is shown so engaged in the drawing. The arm 63 lies in front of the arm 61 in such a position as to have its cam edge 15 engaged by the upper end of the finger 47 when said finger stands in its forward or non-clear position. In the position of the parts shown in the drawings, the last operation of the totalizer 30 was one that cleared said totalizer, causing the finger 47 to move to its rear position. After 20 the last digit of the total was copied, the cross truck jumped to the right with finger 47 in its rear position, said finger running under the cam 62 and elevating the arm 61. It will be perceived that the linkage is such that the elevation of the 25 arm 61 causes the arm 63 to swing downward to the position shown in the drawings where it is ready to be displaced by the finger 47 when a number is added into the register. It will also be perceived that the cross truck 26 may be reciprocated an indefinite number of times without 30 making any change in this linkage. But, if in some computing column a number be written and registered in the cross totalizer 30, bringing said totalizer to a non-clear condition or state, then 35 the finger 47 will be moved to its forward position, and when the cross totalizer jumps back after writing the last digit of the number the finger 47 will strike the cam 64 and elevate the arm 63 and depress the arm 61. Once the linkage 40 is moved to this position, with the arm 63 up and the arm 61 down, an indefinite number of numbers may be registered in the cross totalizer 30, and it may be jumped back an indefinite number of times without changing the linkage. 45 But, if in any computing column the total be copied from the cross totalizer correctly and subtracted, bringing said totalizer to zero, then on the jump-back of the cross truck the linkage will be moved to its alternative position with the 50 arm 61 up and the arm 63 down.

It will be perceived that this linkage is a sort of index to the condition of the cross totalizer and that it is changed from one of its alternative positions to the other under the control of said 55 totalizer and of the finger 47 by power derived from the travel of the carriage.

This linkage can be used to actuate various forms of clearance proof mechanism. In the preferred embodiment of the invention a signal is given by any change in the position of the linkage. When it is moved from its non-clear to its clear position it causes a star to be printed automatically, and when it is moved from its clear to its non-clear position it causes a square to be printed automatically. It will be perceived that since the motion of the linkage is caused by the jump-back of the cross truck, which in turn is caused by the stepping of the carriage from units to sub-units position, these signs will be printed, 70 in sub-units position immediately following the numbers to which they relate.

The printing of these signs can be effected by various forms of mechanism. In the instance

illustrated in the drawing I have placed a star type on the extreme right-hand one 16 of the type bars, and a type to print a square on the next type bar, and have connected these type bars to be operated by power mechanism. This power mechanism can be of a variety of sorts. The drawings, Figs. 1 and 2, illustrate, more or less conventionally, the power printing mechanism described in the patent to Dorsey No. 0 1,602,756 dated October 12, 1926; but with some slight modification which will be described. The Dorsey patent shows a long power drum extending across the base of the typewriter. In the present instance the type bars are key-operated, 15 except the two under consideration. I have shown only a short drum 65 mounted on the inner end of a short power shaft 66 which in its other end carries a pulley 67 that may be connected with any suitable motor so as to give a 20 continuous rotation to the drum 65. The shaft 66 is shown journaled in a casting 68 secured by screws 70 to the base 5 of the typewriter frame. The casting 68 includes a bracket 71 over-hanging the drum 65 and slotted and otherwise formed 25 to accommodate the Dorsey mechanism. This includes a forward bell crank 72, pivoted in the bracket 71 at 73, and a rear bell crank 74 pivoted at 75. Each of these bell cranks is connected by a link 76 with a bell crank 14 of the typewriter 30 resembling generally those used in the ordinary Remington #12 type action. The bell crank 72 has pivoted thereto at 77 an eccentric contact device or cam 78 which is controlled by a spring 80, and is adapted to be set into operation by 35 means of the push link 81 pivoted at its upper end at 82 to a lever 83 of the first order, which lever is pivoted at 84 to the bracket 71. All of this mechanism corresponds exactly to that associated with the forward one of Dorsey's two bell 40 cranks, the front end of the lever 83 taking the place of Dorsey's key lever. The rear bell crank 74 has an eccentric contact piece or cam 85 pivoted thereto at 86 and controlled by a spring 87. This contact piece is brought into action by a 45 push link 88, pivoted at 89 to the rear arm of the lever 83. This mechanism is intended to be the same as that associated with Dorsey's rear bell crank, except that the eccentric or cam 85 is started into action by the down stroke of the 50 link 88 instead of by an up stroke, and the shoulder on the piece 85 which this link engages therefore faces up instead of down. The links 81 and 88 are controlled by springs 91, and said links are also suitably guided by pins 92 in substantially 55 the same way as in the Dorsey patent. The whole construction is such that if, with the parts in the positions shown in Fig. 2, the lever 83 be rocked downward at its forward end, the link 81 will give an initial motion to the eccentric cam 78, enough to bring it into contact with the 60 rotating drum 65. This drum will continue the rotation of the cam 78 and on account of the eccentricity of said cam will impart an enforced rocking movement to the bell crank 72 which will 65 actuate the type bar 17 which prints a square. The same rocking motion of the lever 83 will elevate the link 88 and cause it to engage the shoulder of the piece 85. Nothing further will 70 happen with this mechanism until the lever is rocked back to the position shown in the drawings. When that occurs the link 88 will impart a preliminary motion to the eccentric 85 to bring said eccentric into contact with the rotating drum, 75 which drum will complete the motion and operate

the type bar 16 to print a star. At the time when the lever 83 completes its rocking motion as just described the link 88 rubs against the pin 92 and is moved out of engagement with the part 85 so that as soon as said part completes its motion 5 and the arm 74 of the bell crank is swung rearwardly the part 85 will be snapped back to its normal position by the spring 87. A similar thing, of course, happens at the end of the operation of the eccentric 78. 10

The third bell crank on the bracket 52, namely, the one whose upstanding arm is numbered 56, has its horizontal arm to the rear of said plate 52, the bail part of the bell crank extending under the plate and its horizontal arm 92 extending 15 leftward from the pivot pin 60. This leftward extending arm is connected by link 93 with the lever 83 as shown in Figs. 1 and 2. The construction is such that whenever the cross totalizer 30 is cleared the succeeding jump-back of the 20 cross truck causes the finger 47 to raise arm 61 which swings the link 57 rightward and moves the arm 56a and link 93 upward, swings lever 83 to the position shown in Fig. 2 and causes the power drum to print the star. All of this mechanism will remain quiescent until at some jump 25 back of the cross truck the finger 47 engages the arm 63 and elevates said arm which will move link 57 leftward and arms 56a and 83 downward, 30 causing the drum 65 to actuate the type bar 17 to print a square.

In view of the fact that the stop bar 38 of the cross truck, is in practice adjusted to different lengths appropriate to the width of the particular totalizer to be used on the said cross truck, it 35 seems desirable, although not necessary, to adjust the arms 61 and 63 in harmony with the adjustment of the truck 26; and provision for such an adjustment is shown in the drawings. 40 To this end, the pivot pins 60 for the bell cranks 54, 61 and 55, 63 are not mounted directly on the plate 52 but are mounted on an auxiliary plate 94 secured to the front face of the plate 52 by means of a milled head screw 95 screwed into the back of the plate 94 and passing through an elongated slot 96 in the plate 52. A bar 97 may be secured to plate 52 and provided with notches 98, and said plate 94 may have one or more teeth 100 adapted to engage in said notches. The construction is such that the plate 94 and the contact mechanism as a whole including the linkage 54, 65, 57 may be adjusted right and left on the plate 52. In order to enable this to be done the left-hand end of the link 57 may have in it a 55 succession of holes 101 for the pivot pin 58 of the lever arm 56, said holes spaced the same as the notches 98.

In Fig. 1 the cross truck is shown jumped as far back to the right as the stop bar 38 will permit it to go and the master wheel 31 is shown one space to the left of the left-hand wheel of the totalizer, and this is a desirable adjustment of the parts, although not necessary. If now the cross truck be picked up and a number be added in one of the higher wheels of this totalizer the 60 comb 42 will be forced to its rear position. This would rock the finger 47 to its forward position. Said finger 47 is, however, behind the free end of the lever arm 63 and cannot move to its forward position at this time. This situation may be 65 provided for in various ways. As shown in the drawings, the arms 45 and 47 are made of separate pieces both pivoted at 46 but capable of independent rocking. These two arms are connected by a tension spring 102 and the arm 47 75

- has a lug 103 overlying the arm 45 and limiting the relative motion of the two arms in one direction. In case the first number to be added on the totalizer was on one of the higher wheels and 5 the comb 42 was forced to its non-clear position, it would depress the arm 45 and press the arm 47 against the rear face of the arm 63, whereupon the spring 102 would be stretched. The parts would remain in this position until in the leftward travel of the totalizer 30 the finger 47 passed from behind the arm 63 when said finger would snap forward to its proper position, and it would operate the arm 63 on the jump-back of the totalizer.
- 15 The opposite situation could also occur. If, for example, in the machine shown in the drawings the total to be copied should be exactly \$3,000, then the totalizer will be clear as soon as the "3" is written and the finger 47 would 20 tend to move to its rear position. At this time, however, it would be in front of the arm 61 and could not so move. The rearward motion of this finger 47 is, however, not positive but is produced only by the spring 48. No harm would be done 25 therefore because the finger 47 would merely rub against the front face of the arm 61 for one or two letter space steps of the carriage leftward, whereupon said finger would be free from the arm 61 and could snap to its rear position ready 30 to operate said arm on the jump-back of the carriage.
- One of the advantages of my invention resides 35 in the fact that it is applicable to a great variety of different kinds of work. In Fig. 1 the machine is set up for a distribution job, having four columns defined by the four vertical totalizers. The total amount of a bill is written in column 21. Totalizer 21 is not provided with a subtract cam 36 and this amount will therefore 40 be added in the cross totalizer 30. If the work has been correctly done the cross totalizer will have been cleared before this number is written. In other words, in the initiation of the work the parts will stand in the position shown in Fig. 1. 45 As soon as the amount is written in column 21 it will be added in the cross totalizer, the finger 47 will be moved to its forward position, and on the jump-back of the cross footer the mechanism will be actuated so that the square 104 will be 50 automatically printed after the amount. In the first line of the paper illustrated in Fig. 1, this amount was \$51.25, of which \$26.00 was chargeable to department A. This amount written in column 22 is subtracted but does not clear the 55 cross totalizer. The balance of this amount, namely, \$25.25 being chargeable to department B is written in column 23 and subtracted from the cross totalizer. If this work is done correctly it will clear the totalizer and cause a star to be 60 printed automatically in sub-units position in column 23. When the carriage is drawn back to write the second amount \$73.00 in column 21, the writing of this amount changes the cross totalizer from clear to not clear, and will consequently 65 result in the automatic printing of the square 104 in sub-units position. This amount is distributed in all three succeeding columns, the cross totalizer not being cleared until the \$13.00 in column 24 is written. Since the writing of 70 this number clears the totalizer, the power mechanism will automatically print a star in the sub-units position of that column. When the third amount \$41.65 is written in column 21, the square will automatically be written after it as before. 75 This amount all belongs to department A and is

copied in column 22, clearing the cross totalizer and printing the star in the sub-units position of that column.

Another common form used in these machines is a loose-leaf ledger having four columns, one for pick-up of the old balance, one for debits, one for credits, and one for the new balance. When in writing a line on one of these forms the work is done correctly the cross totalizer is always clear before picking up the old balance, and it is cleared by writing the new balance. On one of these sheets, therefore, without any attention on the part of the operator, as long as the work is done correctly a star will automatically appear after each new balance item and a square will automatically appear after each pick-up item. If numbers be written in a column and added in the cross totalizer, and the machine then set for subtraction, and the total printed, thus clearing the cross totalizer, a square will be automatically 20 printed after the first number in the column proving that the cross totalizer was clear before that number was written, and a star appearing automatically after the total will be proof that the total has been correctly copied. 25

In short the construction is such that in any or all operations on this machine the appearance of a square following a number written in any computing column is proof that the cross totalizer was clear before that number was written, and 30 the appearance of a star following any number written in a computing column is proof that the writing of that number cleared the cross totalizer; and any number written in a computing column and not followed either by a square or a star 35 is proof that the cross totalizer was not clear before that number was written and that the act of writing the number did not clear the cross totalizer. This is true no matter in what way the numbers are written so long as they are in computing columns with the computing mechanism in operation.

Various changes may be made in the details of construction and arrangement without departing from the invention. 45

What I claim as new and desire to secure by Letters Patent, is:—

1. In a computing machine, the combination with a totalizer and its actuator the one traveling relative to the other, of a device in said totalizer which occupies one position when the totalizer is clear and another position when the totalizer is not clear, a signal controlled by said device and by the said relative travel to indicate a clear state of the totalizer, and another signal controlled by 55 said device and by such relative travel to indicate a change of the state of the totalizer to not clear.
2. In a computing machine, the combination with a totalizer and its actuator the one traveling relative to the other, of a device in said totalizer which occupies one position when the totalizer is clear and another position when the totalizer is not clear, and a signal mechanism controlled by said device and by such travel and acting only immediately following the complete 60 computation of the first number inserted in said totalizer after a clearance of said totalizer to indicate that the totalizer was clear before said first member was inserted.
3. In a computing machine having a totalizer and a master wheel therefor having relative step by-step travel, a non-clear indicating mechanism automatically brought into operation by such travel following the registering in the totalizer 70 75

of the last digit of the first number to be registered in the totalizer after a clearance thereof.

4. In a computing machine, the combination with a totalizer and an actuator therefor the one traveling relative to the other, of a device in said totalizer which occupies one position when the totalizer is clear and another position when the totalizer is not clear, a signal controlled by said device and by such relative travel and acting on the first excursion only following a change in the state of the totalizer from clear to not clear, and another signal controlled by said device and by such relative travel and acting on the first excursion only following a change in the state of said totalizer from not clear to clear.

5. In a computing machine, the combination with a totalizer, an actuator for registering in said totalizer the digits of a number one digit after another, and means for printing said digits, means acting automatically to print a distinctive sign immediately following the printing and registering of the last digit of the first number to be registered in said totalizer following clearance thereof.

6. In a computing machine, the combination with a totalizer, an actuator for registering in said totalizer the digits of a number one digit after another, and means for printing said digits, of means acting automatically to print a distinctive sign immediately following the printing and registering of the last digit of the first number to be registered in said totalizer following clearance thereof, and means acting automatically to print another distinctive sign immediately following the printing and registering of the last digit of a number the registering of which clears the totalizer.

7. In a combined typewriting and computing machine, the combination with typewriting mechanism including type-bars, register mechanism, and means for operating said register mechanism by the typewriter numeral keys one digit at a time, of a type-bar adapted to print a designating character and means acting automatically to operate said type-bar following the printing and registering of the last digit of the first number to be registered in said mechanism following a clearance thereof.

8. In a computing and recording machine, the combination with a totalizer, an actuator therefor, and a device in said totalizer which occupies one position when the totalizer is clear and another position when the totalizer is not clear, of mechanism controlled by said device and actuated after the registration of the last digit of a number, said mechanism having two positions to one of which it is moved after said device has been moved to its clear position and to the other of which said mechanism is moved after said device has moved to its non-clear position; a characteristic signal operated by the first said motion of said mechanism and another characteristic signal operated by the second said motion of said mechanism.

9. In a computing and recording machine, the combination with a totalizer, an actuator therefor, and a device in said totalizer which occupies one position when the totalizer is clear and another position when the totalizer is not clear, of mechanism controlled by said device and actuated after the registration of the last digit of a number, said mechanism having two positions to one of which it is moved after said device has been moved to its clear position and to the other of which said mechanism is moved after said de-

vice has moved to its non-clear position; a type caused by the first said motion of said mechanism to print a characteristic sign and another type caused by the second motion of said mechanism to print another characteristic sign.

10. The combination with a register and means for actuating it to register numbers and to clear said register, of a feeler device having one position when said register is clear and another position when said register is not clear, a shiftable device having two positions, said feeler device and said shiftable device having relative motion, said feeler device by reason of such relative motion shifting said shiftable device to one position when the register is clear and to the other position when said register is not clear, and said shiftable device remaining in said other position during subsequent such relative motions as long as the register is not clear.

11. The combination with a register and means for actuating it to register numbers and to clear said register, of a feeler device having one position when said register is clear and another position when said register is not clear, a shiftable device having two positions, and having two parts for contact with said feeler device, said feeler device and said shiftable device having relative motion in two paths one corresponding to each of said contact parts, said feeler device by such relative motion when the register is cleared displacing one of said contact parts out of one of said paths and placing the other of said contact parts into the other of said paths, and said feeler device by such relative motion when the first number is registered displacing the said other contact part from said other path and placing the first contact part in the first path.

12. The combination with a register, and means for actuating it, of a feeler device having one position when the register is clear and another position when the register is not clear, two contact parts, said contact parts and said feeler device having relative motion upon an actuation of said register such that said feeler device when in its clear position will come within the range of one of said contact devices and when in its not clear position will come within range of the other said contact device, a signal device automatically operated by the first contact only of said feeler with one of said contact devices, and another signal device operated by the first contact only of said feeler device with the other said contact device.

13. The combination with a register having a feeler device to detect clear and non clear states of said register, and means for actuating said register, of a linkage comprising two bell cranks having parallel arms connected by a link and having oppositely extending arms, means for producing a relative motion between said feeler device and said linkage, said feeler device acting on and shifting one or the other of said oppositely extending arms depending upon its position at the time, and means whereby a characteristic signal is operated upon each shifting of said linkage.

14. The combination with a register having a feeler device to detect clear and non clear states of said register, and means for actuating said register, of a linkage comprising two bell cranks having parallel arms connected by a link and having oppositely extending arms, means for producing relative motion between said feeler device and said linkage, said feeler device acting on and shifting one or the other of said oppositely ex-

- tending arms depending upon its position at the time, and means whereby the shifting of one of said arms causes one sign to be printed and whereby the shifting of the other arm causes another sign to be printed.
15. The combination with a jumping totalizer having a clearance feeler device including a finger (47), mechanism including two contact devices one in the path of the jump-back of said finger when the latter shows clear and the other in the path of said finger when said finger shows not clear, means so connecting said two contact devices with each other that when one of them is displaced by said finger it moves the other contact device into position to be actuated by said finger, and signal mechanism operated by the shifting of said contact devices.
16. The combination with printing mechanism, computing mechanism including a register, and a source of power, of means for detecting clear and not clear states of said register, and means whereby said detecting means causes said source of power to actuate said printing mechanism to print one characteristic sign at a change in the state of the register from clear to not clear and to print another characteristic sign at each change in the state of the register from not clear to clear.
17. The combination with printing mechanism including two special types, computing mechanism, and means for detecting clear and non-clear states of said computing mechanism, of a rotating power drum, a rocking lever, means whereby the act of rocking said lever in one direction operatively connects one of said special types to said drum and the act of rocking said lever in the opposite direction operatively connects the other special type to said drum, and means whereby said detecting means causes rocking of said lever.
18. The combination with a jumping totalizer, a stop adjustable to regulate the extent of the jump-back of said totalizer and feeler mechanism in said jumping totalizer, of mechanism operated by said feeler mechanism on the jump-back of the totalizer, said mechanism having parts thereof mounted for bodily adjustment relative to other parts thereof to conform to the adjustment of said stop.
19. The combination with a traveling register, a feeler to detect the state of said register and a cam adjacent to the path of travel of said register, of two arms one controlled by said feeler and the other a finger for operating said cam and said arms yieldingly connected so that in case the state of said register should be changed when said finger is in front of said cam the feeler can move notwithstanding said finger is arrested by said cam.
20. In a typewriting calculating machine, a counting mechanism comprising a set of counting elements for a plurality of orders, mechanism for printing numerals and shifting said counting elements accordingly one order at a time, means for printing a distinctive sign, a member having a continued forward movement during the successive steps of normal operation of the machine, automatic operating means for said distinctive sign printing means controlled by said member so as to be started automatically at a predetermined point in the movement of said member,
- and a supplementary control for said operating means to render the same dependent upon the condition of said counting mechanism.
21. In a machine of the class described, a counting mechanism, a traveling paper carriage, a "clear" sign printing mechanism, operating means for said "clear" sign printing mechanism including a source of power, means controlled by movement of said carriage for starting said operating means, and means rendering the operation of said printing mechanism dependent upon the condition of said counting mechanism.
22. In a machine of the class described, a counting mechanism, a member having a continued forward movement during the successive steps of the normal operation of said machine, said member being adjustable along its line of motion, printing members including a "clear" sign printing mechanism, automatic operating means for said printing mechanism, means controlled by said first-named member for starting said operating means at a predetermined point in the forward movement of said member, and a supplementary control rendering the operation of said last-mentioned means dependent upon the condition of said counting mechanism.
23. In a combined typewriting and computing machine, typewriting mechanism including clear sign printing mechanism and a step-by-step-moving carriage, a member secured to said carriage and adjustable longitudinally thereof, operating means for said clear sign printing mechanism automatically set into operation by said member at a stage in the operation of the machine determined by the adjustment of said member, and means for rendering the operation of said clear sign printing mechanism dependent upon the condition of said counting mechanism.
24. A combined typewriting and computing machine having a traveling carriage, a totalizer, and mechanism for printing numbers one digit at a time and entering said numbers in said totalizer, the combination which includes a rotating power member, a type for printing a distinctive sign, means for operating said type including a device capable of engaging said power member to be operated thereby once only, means controlled by movement of said carriage for bringing said device into engagement with said power member, and means rendering the operation of said engaging means dependent on the condition of said totalizer.
25. In a combined typewriting and computing machine having numeral printing types and a paper carrier, a carriage imparting relative movement to said types and paper carrier, means to actuate said types and carriage to print the digits of a number one at a time in each of a plurality of columns and a cross-footing totalizer in which the printed numbers are entered; the combination which includes a special type for printing a distinctive sign, a device adjustable with respect to the travel of said carriage, means for sensing the condition of said totalizer, and means brought into operation by said device at a stage in the operation of the machine determined by the adjustment of said device and acting automatically under the control of said sensing means to print said sign.

ROBERT H. STROTHER.
